United States Patent Office

Des. 203,762
Patented Feb. 15, 1966

203,762

FOOD PATTY FORMING DEVICE OR SIMILAR ARTICLE

Gordon V. Dayton, 34 SE. 66th Ave., Portland, Oreg.

Filed July 1, 1965, Ser. No. 85,981

Term of patent 14 years

(Cl. D44—1)

FIG. 1.

FIG. 2.

FIG. 3.

FIG. 4.

FIG. 5.

FIG. 1 is a top plan view of a food patty forming device or similar article showing my new design, the parts being shown in closed position;

FIG. 2 is a side elevation as viewed from the bottom in FIG. 1;

FIG. 3 is a bottom plan view as viewed from the bottom in FIG. 2;

FIG. 4 is an end elevation viewed from the left in FIG. 2; and

FIG. 5 is an end elevation viewed from the right in FIG. 2.

I claim:

The ornamental design for a food patty forming device or similar article, as shown.
